UNITED STATES PATENT OFFICE

CHARLES W. MUELLER, OF ST. LOUIS, MISSOURI, ASSIGNOR TO LEWIS INVISIBLE STITCH MACHINE COMPANY, OF ST. LOUIS, MISSOURI, A CORPORATION OF MAINE

SEWING MACHINE

Application filed November 7, 1928. Serial No. 317,726.

This invention relates to new and useful improvements in sewing machines generally, although more particularly to a blind stitch sewing machine for forming and retaining creases in trousers.

Among the several objects of my invention are to provide a sewing machine with a stitch forming mechanism and a work presenting mechanism whereby a trouser leg, either in its completed tubular condition or in its flat condition prior to either or both of the leg seams being formed, may be fed through the machine and a line of blind stitches formed in the inner face thereof and functioning to provide and retain a crease in said trousers, and to provide a seam for such purpose which is elastic so as to permit of the fabric giving when placed under strain such as occurs when the wearer occupies a sitting position.

With these and other objects in view which will more fully appear, the nature of the invention will be more clearly understood by following the description, the appended claims, and the several views illustrated in the accompanying drawings.

In the accompanying drawings which illustrate one form of my invention:

Figure 1 is a front elevation of a blind stitch sewing machine embodying my invention,

Figure 2 is a left hand end elevation thereof, the end cap being removed to better disclose the work presenting mechanism,

Figure 3 is an enlarged top plan view of the work presenting mechanism, the view being taken directly above the presser foot and showing the needle in cooperative position at the beginning of its penetrating movement,

Figure 4 is an enlarged sectional view taken on the line 4—4 of Figure 3,

Figure 5 is an enlarged transverse sectional view taken on the line 5—5 of Figure 3, the view showing the fabric in operating position and the plunger at the lower end of its stroke,

Figure 6 is a view similar to Figure 5 but showing the plunger at the upper end of its stroke and the needle in position in the fabric,

Figure 7 is a perspective view of the upper end of the plunger,

Figure 8 is a front view of a pair of trousers embodying my invention,

Figure 9 is an enlarged transverse section of one of the trouser legs showing in a diagrammatic manner the location of the crease or fold retaining means, and

Figure 10 is an enlarged detailed view looking at the inner face of the fabric and showing the line of stitches which connects the inner face of the fabric on opposite sides of the fold.

Like reference numerals designate corresponding parts throughout the several figures of the drawings.

The present invention is illustrated herein as embodied in a blind stitch sewing machine of the well known "Lewis" type, and includes a base or bed plate 5, a post or standard 6 and an overhanging arm 7 which supports at its outer end a stitching head 8. Projecting laterally from the standard 6 is a work arm 9 which terminates at its free end under the stitching head 8.

The machine includes a stitch forming mechanism and a work presenting mechanism which cooperate to form a line of single thread chain stitches and anchor said stitches in the opposite inner faces of a trouser leg on opposite sides of the seam thereof.

In order to understand the operating parts of this machine and the function, it is advisable to first describe the trousers and the crease seam which is produced by this machine and the method of producing such seam. Therefore, referring particularly to Figures 8, 9 and 10, A designates a bifurcated garment, such as a pair of trousers, and includes leg portions a—a, each including a front portion 10 and a back portion 11 which are connected by an inside leg seam 12 and an outside leg seam 13. Each leg portion a is provided with longitudinally extending front and rear folds or creases 14—14. The trousers as thus far described are of the usual construction.

In order to retain each fold or crease 14, I have provided a means comprising a line of connected blind stitches which I have desig-

nated B and have illustrated the same dia-
grammatically in Figure 9. These stitches
enter and emerge from the inner face only
of the fabric and therefore they are not ex-
posed to the outer face thereof. I preferably
employ elastic stitches as the same permit
the fabric to give when placed under strain
such as occurs when the wearer occupies a sit-
ting position. Although several types of
elastic stitches may be employed, I prefer to
use what is known as a single thread chain
stitch formation. Therefore the line B of
stitches includes a series of connected and
uniformly spaced anchored needle thread
loops b. Each loop b enters the inner face
of the fabric and emerges from said inner
face on each side of the fold 14 as indicated
at 15 and 16 respectively. Each loop b in-
cludes two portions 17 and 18 which extend
twice across the fold 14 and are disposed at
an angle to each other, the portion 17 extend-
ing at right angles to the fold and the portion
18 extending at a substantial angle thereto,
the degree of inclination being dependent on
the length of stitch, that is, the distance be-
tween points of needle penetrations. The
portion 18 is the closed end of the loop and
this loop is anchored by the next formed
needle thread loop, as is clearly shown in Fig-
ure 10. The needle thread loops b enter and
emerge on each side of the fold 14 along lines
which are fairly close to the fold and are
spaced equidistant therefrom, thus not only
maintaining the fold but also maintaining
the fold in a uniform manner throughout its
length. The method employed in producing
this fold retaining means is disclosed in my
co-pending application Serial No. 309,489,
filed Oct. 1, 1928, and the trousers produced
by my method and by the machine forming
the subject matter of the present applica-
tion is disclosed in my copending applica-
tion Serial No. 290,071, filed July 3, 1928.

Rigidly attached to the lower end of the
stitching head 8 is a presser foot 19 having a
work receiving opening 20 formed therein.
The upper face of the presser foot, on oppo-
site sides of the opening 20, is provided with
transversely disposed needle guides 21 and
22.

A needle 23 is adapted to be reciprocated
across the opening 20 and cooperate with said
guides 21 and 22 during such reciprocation.
This needle 23 is fixed to a needle arm 24
which is pivoted as at 25 to the stitching head
8, the pivot being disposed directly above the
opening 20. The needle arm 24 is provided
with a work arm 26 to which is pivotally con-
nected as at 27 one end of a driving link 28,
the other end of the link being pivotally con-
nected as at 29 to an eccentric pin fixed to a
driven gear 30 journaled on the head 8. The
gear 30 is driven by a gear 31 fixed on the
main driving shaft 32 which is journaled in
the overhanging arm 7. Thus when the shaft

32 is rotated the gear coupling 30—31 will ro-
tate the eccentric pin 29 and as a result the
link 28 will oscillate the needle 23 about its
fulcrum 25 in a direction across the opening
20 of the presser foot. A looper mechanism
which cooperates with the needle and the
single thread carried thereby to form a line
of single thread chain stitches, is indicated as
a whole by the reference numeral 33, and in-
asmuch as this looper mechanism is of well
known construction and is fully disclosed in
my prior Patent 1,539,399, May 26, 1925, it is
thought that further description thereof is
unnecessary.

Cooperating with the underside of the
presser foot 19 for feeding the fabric across
the work arm 9 and in a direction at right
angles to the path of needle movement, I have
provided a feed mechanism which includes a
4-motion feed dog 34. This feed dog is given
its four motions by a feed mechanism which I
have indicated generally by the numeral 35.
This feed mechanism is of the well known
type and is driven from the main rotary shaft
32 through the medium of driving connec-
tions extending through the standard 6 and
work arm 9, and it is therefore thought that
a detailed description thereof is unnecessary.
A vertically reciprocatory plunger 36 is sup-
ported in the free end of the work arm 9 in
the usual manner, and means are provided
for reciprocating this plunger in timed rela-
tion to the feed dog movements and to the
needle reciprocations, in a manner well un-
derstood by those skilled in this art and there-
fore a detailed description of the operating
means for reciprocating the plunger is
thought to be unnecessary. This plunger is
located directly below the opening 20 in the
presser foot and is adapted to project the
work or fabric upwardly into said opening
whereby said fabric will be engaged by the
needle 23. The upper end of the plunger 36
is provided with spaced upwardly extending
fabric engaging arms 37—37 which form a
resultant vertical slot 38 therebetween. A
retaining finger 39 has its front end secured
to the presser foot 19 in front of the opening
20 by means of a screw 40. This finger ex-
tends rearwardly and thence downwardly
into the opening 20 and terminates in a hori-
zontal portion 41 which is disposed below the
path of needle reciprocations and directly
above the lower surface of the foot 19. The
extreme rear end 42 of the retaining finger
39 terminates immediately in rear of the path
of needle reciprocation and in advance of and
in spaced relation to the rear wall 43 of the
presser foot opening 20. The retaining finger
39 is disposed centrally of the opening 20 and
extends generally in the line of feed and is lo-
cated in a position to enter the slot 38 in the
plunger when the plunger is moved up-
wardly.

In the operation of my machine, the trouser

leg either in its flat condition or in its finally formed tubular condition, is positioned below the presser foot 19 and above the feed dog 34, with the needle in the beginning of its stroke or in the position shown in Figures 1 and 5. Upon rotation of the main shaft 32, the plunger 36 will be elevated to the position shown in Figure 6, thus elevating the fabric on opposite sides of the retaining finger 39, and forming spaced nodes n and n' in the material on opposite sides of the center line of feed, and a downwardly extending centrally located node n^2 which is retained by the retaining finger 39. While the nodes n and n' are held by the plunger, the needle 23 is given its forward or penetrating movement to the position shown in Figure 6, the needle first entering the node n , then emerging therefrom, then entering the node n' and then emerging therefrom. In this movement, the needle enters and emerges from the upper face of the fabric only and consequently the stitches ultimately produced by the stitch forming mechanism will be invisible from the lower face of the fabric which lower face is the outer face of the trousers. The plunger 36 then begins its downward movement and simultaneously the needle 23 begins its return movement. Simultaneously with the return movement of the needle the looper of the looper mechanism 33 is actuated to cooperate with the needle thread and thereby form a loop of needle thread and position the same in readiness to be entered by the needle during the next forward movement thereof. It will be understood that after the needle has been retracted from the fabric the feed dog 34 is given its feeding stroke to feed the fabric a stitch length distance.

From the foregoing, it will be apparent that I have provided a means below the presser foot for projecting spaced nodes of fabric or material simultaneously upwardly through the opening of the foot into needle penetrating position whereby the needle will in succession enter each node and emerge therefrom; that the path of needle oscillation is in a plane transverse to the line of feed; that the nodes of material are projected upwardly on opposite sides of the center line of feed and that the upper end of the plunger is provided with upwardly extending material engaging arms which are spaced apart a distance sufficient to receive the retaining finger and the material therearound.

It is of course to be understood that the details of structure and arrangements of parts may be variously changed and modified without departing from the spirit and scope of my invention.

I claim:

1. In a sewing machine, the combination with a presser foot having an opening, of a feeding mechanism cooperating with said foot, a needle mechanism including a

threaded needle reciprocating above the opening of the foot, a retaining finger located within the opening of the foot and disposed below the path of needle reciprocation, and means located below the foot for projecting spaced nodes of material simultaneously upwardly through the opening of the foot on opposite sides of the finger and into needle-penetrating position whereby the needle will in succession enter each node and emerge therefrom. 70

2. In a sewing machine, the combination with a presser foot having an opening, of a feeding mechanism cooperating with said foot, a needle mechanism including an oscillatory threaded needle fulcrumed on a fixed pivot directly above the opening in the foot, a retaining finger located within the opening of the foot and disposed below the path of needle reciprocation, and means located below the foot for projecting spaced nodes of material simultaneously upwardly through the opening of the foot on opposite sides of the finger and into needle-penetrating position whereby the needle will in succession enter each node and emerge therefrom. 80

3. In a sewing machine, the combination with a presser foot having an opening, of a feeding mechanism cooperating with said foot, a needle mechanism including an oscillatory threaded needle fulcrumed on a fixed pivot directly above the opening in the foot, the path of needle oscillation being in a plane transverse to the line of feed, a finger fixedly secured at its front end to the foot at a point in front of the opening therein, said finger extending rearwardly and terminating at a point in spaced relation to the rear end of the presser foot opening, and means located below the foot for projecting spaced nodes of material simultaneously upwardly through the opening of the foot on opposite sides of the finger into needle-penetrating position whereby the needle will in succession enter each node and emerge therefrom. 95

4. In a sewing machine, the combination with a presser foot having an opening, of a feeding mechanism cooperating with said foot, a needle mechanism including a threaded needle reciprocating above the opening of the foot, a stationary retaining finger carried by the foot, and means located below the foot including a vertically reciprocating plunger cooperating with said retaining finger for projecting spaced nodes of material simultaneously upwardly through the opening of the foot into needle-penetrating position whereby the needle will in succession enter each node and emerge therefrom. 100

5. In a sewing machine, the combination with a presser foot having an opening, of a feeding mechanism cooperating with said foot, a needle mechanism including an oscillatory threaded needle fulcrumed on a fixed pivot directly above the opening in the foot, 115

the path of needle oscillation being in a plane transverse to the line of feed, a stationary retaining finger carried by the foot, and means located below the foot including a vertically reciprocatory plunger cooperating with said retaining finger for projecting spaced nodes of material simultaneously upwardly through the opening of the foot into needle-penetrating position whereby the needle will in succession enter each node and emerge therefrom.

6. In a sewing machine, the combination with a presser foot having an opening, of a feeding mechanism cooperating with said foot, a needle mechanism including a threaded needle reciprocating above the opening of the foot, a stationary finger extending rearwardly in the line of feed from the front end of the foot and having its rear end free and located within the opening of the foot, and means disposed below the foot and cooperating with the finger for projecting spaced nodes of material upwardly through the opening in the foot on opposite sides of the finger into needle-penetrating position whereby the needle will in succession enter each node and emerge therefrom.

7. In a sewing machine, the combination with a presser foot having an opening, of a feeding mechanism cooperating with said foot, a needle mechanism including an oscillatory threaded needle fulcrumed on a fixed pivot directly above the opening in the foot, the path of needle oscillation being in a plane transverse to the line of feed, means located below the foot for projecting spaced nodes of material simultaneously upwardly through the opening of the foot on opposite sides of the central line of feed into needle-penetrating position whereby the needle will in succession enter each node and emerge therefrom, a stationary finger extending rearwardly in the line of feed from the front end of the foot and having its rear end free and located within the opening of the foot, and means disposed below the foot and cooperating with the finger for projecting spaced nodes of material upwardly through the opening in the foot on opposite sides of the finger into needle-penetrating position whereby the needle will in succession enter each node and emerge therefrom.

8. In a sewing machine, the combination with a presser foot having an opening, of a feeding mechanism cooperating with said foot, a needle mechanism including a threaded needle reciprocating above the opening of the foot, a stationary finger extending rearwardly in the line of feed from the front end of the foot and having its rear end free and located within the opening of the foot, and a vertically reciprocatory plunger cooperating with the finger for projecting spaced nodes of material upwardly through the opening in the foot on opposite sides of the finger into

needle-penetrating position whereby the needle will in succession enter each node and emerge therefrom.

9. In a sewing machine, the combination with a presser foot having an opening, of a feeding mechanism cooperating with said foot, a needle mechanism including a threaded needle reciprocating above the opening of the foot, and means located below the foot including a vertically reciprocatory plunger and a cooperating stationary retaining finger for projecting spaced nodes of material simultaneously upwardly through the opening of the foot into needle-penetrating position whereby the needle will in succession enter each node and emerge therefrom, the upper end of the plunger being provided with spaced upwardly extending material-engaging arms spaced apart a distance sufficient to receive the retaining finger and the material therearound.

10. In a sewing machine, the combination with a presser foot having an opening, of a feeding mechanism cooperating with said foot, a needle mechanism including a threaded needle reciprocating above the opening of the foot, a stationary finger extending rearwardly in the line of feed from the front end of the foot and having its rear end free and located within the opening of the foot, and means disposed below the foot including a reciprocatory plunger and cooperating with the finger for projecting spaced nodes of material upwardly through the opening in the foot on opposite sides of the finger into needle-penetrating position whereby the needle will in succession enter each node and emerge therefrom, the upper end of the plunger being provided with spaced upwardly extending material-engaging arms spaced apart a distance sufficient to receive the retaining finger and the material therearound.

In testimony whereof I hereunto affix my signature.
